UNITED STATES PATENT OFFICE

PAUL ALPHONSE HUBERT MOSSAY, OF IPSWICH, ENGLAND, ASSIGNEE TO MOSSAY & COMPANY, LIMITED, OF LONDON, ENGLAND, A CORPORATION

CRANE

Application filed August 15, 1928. Serial No. 299,659.

My invention relates to cranes; and its general object is to provide a new and improved crane, i. e., a light mobile crane or machine which may be readily moved from place to place and otherwise controlled and manipulated, all by hand.

To the above and other ends which will subsequently appear, the invention consists in the features of construction, combinations of devices and arrangements of parts herein-
10 after described and particularly pointed out in the claims.

In carrying out the invention in the present instance, I provide a light skeletonized structure preferably made up of angle bars comprising a generally triangular base or support with the crane post or standard fixed rigidly thereto and rising therefrom, pivotally supporting a jib, boom or material-lifting devices adapted to swing in a vertical plane having a constant relationship with the platform or mobile member and the superstructure or standard. The platform or mobile member is supported on three ground wheels
20 disposed in general triangular formation so as to provide a three-point support, two of the wheels being arranged in a pair at the sides of the structure and settable in variable position by means of a linkage interconnection. The third wheel which is preferably arranged at the rear is also variably settable and the construction is such that the crane as a whole can be used as a turntable around a center within the wheel base or moved along
25 straight paths at right angles to each other or swivelled about a center outside the wheel base.

The adjustment of the wheels is effected by a detachable bar in the nature of a lever arm
40 which is adapted to position in sockets rigid with the pivotal supports of the wheels, the bar also being employed when desired as a tow-bar to effect bodily and pivotal movements of the crane. The invention further
45 comprises novel locking means for positively locking all of the wheels in predetermined set positions so as to insure movements of the crane whether traversing or swivelling in predetermined directions under impulses
50 communicated by the operator.

The invention will be described specifically in detail in connection with the accompanying drawings, wherein

Fig. 1 is a side elevation of the crane or apparatus as a whole. 55

Fig. 2 is a plan view thereof but with the standard or superstructure sectioned away.

Fig. 3 is a fragmentary front elevation, parts being sectioned away for the sake of clearness. 60

Fig. 4 is a fragmentary enlarged horizontal sectional view taken on a plane indicated by the section line 4-4 in Fig. 3 and looking in the direction of the arrows at said line; and

Fig. 5 is an enlarged sectional view taken on a plane indicated by the section line 5-5 in Fig. 2 and looking in the direction of the arrows at said line. 65

In the drawings as clearly appears in Figs. 1, 2 and 3, the platform or base frame of the crane is composed of two side members or angle bars 1 and an end or rear member or angle bar 2. 70

The bars are disposed in triangular formation and the side bars are secured at their ends to the rear bar 2 by gusset plates 3 and 4, rivets 5 or other suitable means being employed to fix the parts in rigid relationship. At the opposite end from the bar 2 the side bars 1 are brought close together and secured in fixed relationship by a casting or weighted member 6 which is interposed between the bars and is formed with an opening indicated at 7 so as to house certain parts hereinafter described, the casting being in the nature of a hood. 75

Rising from the base frame 1-7 is a superstructure or standard which may be constituted by four angle bars 8, two fixed as by angle plates 8^a at their lower ends to the front corner portions of the platform, and two being riveted or otherwise fixed to the casting 6. The angle bars 8 are tied together at their tops so as to constitute a pair of associate side members or upright triangular frames, these frames being preferably connected by lateral cross pieces or bracing 9. The skeleton standard just described provides a support for a skeleton crane jib or boom, designated as a whole by the numeral 80 100

10 and shown in Fig. 1. No particular description of the jib is needed as it may be of any suitable construction. The jib is pivoted to the standard on a horizontal pivot 11 and 5 is restricted to swing in a vertical plane fore and aft of the crane and which bears a constant relationship to the standard and to the platform of the frame. The parts are so related and the weight of the casting 6 is such 10 that the greatest overhang affords stability for the crane as a whole, the casting serving as a convenient counter-weight.

The casting is provided with an eye-member 12 which may serve as an anchorage for 15 the crane jib, it being adapted to be connected to one end of the jib by a chain indicated in Fig. 1 by the numeral 13.

The structure comprising the platform, chassis or truck, the standard, the jib and 20 the load is adapted to be supported on three ground-wheel members constituting a three-point bearing. Two of these wheel members 14 are mounted in a pair, being disposed at opposite sides of the base frame at or near 25 its front end, the third wheel member 15 being disposed at the rear and housed within the casting 6 as hereinafter described, said wheel member 15 being preferably in the form of a double wheel or couple.

30 As will be best understood from Figs. 2-4 each of the wheel members 14 is mounted to rotate on an axle or pivot 16 which extends horizontally from a bearing member 17, said bearing member having an integral vertical 35 portion 18 which is bored out to receive a vertical pivot or swivel 19 on which the bearing member 18 and the wheel 14 are adapted to turn or rotate for swivelling or adjustable movements.

40 As will be clearly understood from Figs. 2 and 3 the gusset plates 3 and 4 project beyond the adjacent corners of the base frame and provide suitable upper and lower bearings for the pivot pins 19, said pins being 45 preferably in the form of screw pivots and clamped in place by nuts 20.

Preferably formed integrally with each bearing member 17-18 are two oppositely extending arms 21 and 22 (Fig. 4).

50 Each arm 22 is formed with an opening indicated at 23 which is adapted to receive a detachable tow-bar or arm 24 terminating in a handle 24^a (Fig. 1). The oppositely extending arms 21 each have pivotally connected to them at 25 links 26 which extend inward and rearward towards each other through openings or slot-ways indicated at 27 in the front bar 2. The links 26 are pivotally connected at their rear ends at 28 to 60 a slide member constituted by two plates 29 spaced apart and connected by pins or rivets 30 which also constitute pivots for rollers 31. Received between the plates 29 on the slide member is a guide bar 32 which extends longitudinally of the base frame, one end of said 65

bar 32 being suitably secured to the frame bar 2 and the opposite end of the bar 32 being secured as by an angle plate 33 to the upright wall of the casting 6. The construction is such that the member or slide constituted by the plates 29 may move freely longitudinally of the guide bar 32, the rollers 31 co-operating with the sides of the guide bar to facilitate such movements. The slide 29, 29 constitutes a connection between the linkages 70 75 26 for controlling the movements of the front wheel elements 14. It will be understood that when swivelling impulses are communicated to one of the wheels 14 as by the operator pushing or pulling on the tow-bar 80 24, corresponding impulses will be transmitted through the linkages to the other wheel 14 to concurrently adjust it, both wheels swinging on their vertical pivots 19.

In Fig. 2, two dotted line positions for the 85 pair of wheels 14 are indicated; one at right angles to the full line position for traversing the crane transversely, the other dotted line position being an intermediate one for affording swivelling movements about a center 90 within the wheel base; the third wheel 15 being, of course, appropriately adjusted for such movements, as will be understood.

Means are provided for positively locking the front wheels in set or adjusted positions, 95 said means comprising, as clearly shown in Figs. 2 and 5, a plurality of holes or openings 34 extending transversely down through the bar 32 and disposed at predetermined points therealong. Corresponding holes 35 100 are formed in the plates 29, and when the holes 35 in the plate and one of the holes 34 in the bar are brought into register they are adapted to receive a locking pin or peg 36 which positively locks the parts together and 105 thus fixes the linkages and locks the wheels 14 in predetermined set positions. This is a highly convenient construction as it enables the operator thereafter to devote his attention exclusively to steering and moving 110 the crane and handling the load carried by it.

The rear double wheel 15 is pivotally supported on a horizontal axle 37 which, as will be understood from Figs. 1 and 2, is supported transversely in a fork 38 having an integral upward extension or pivot 39. The fork 38 and the wheel element 15 are housed within the opening 7 in the hood or casting 6, whereas the pivot 39 bears in an opening 115 120 125 in the roof of said casting and has a reduced portion 39^a projecting upward outside the casting. The reduced portion receives a two-armed member 40 which is clamped by a nut 41 against the shoulder at the top of the pivot 125 portion 39.

One arm of the member 40 is formed with an opening or socket 42 adapted to receive the tow bar 24, the oppositely extending arm 40^a being flattened and formed with a verti- 130

cal hole 43. The hole 43 is adapted, when the wheel 15 is turned on its pivot, to register with any one of a series of holes 44 formed in the top of the casting (Fig. 2) and when thus registered the holes are adapted to receive a locking pin 45 which will positively hold the wheel member 15 set in predetermined adjusted positions ranging through a series to a position at right angles to its fore and aft position as indicated by dotted lines in Fig. 2.

It will be understood that other forms of crane superstructure may be mounted on the triangular base, platform or frame; and also if found desirable winches may be mounted on the supporting frame to operate the jib or boom and lift or otherwise control the load or material as is well understood.

From what has been heretofore said, it is not deemed necessary to describe the mode of operation with any great particularity. It will be understood that to cause the crane to travel forward or backward in the direction of the boom or jib, the front wheels are located and set in a position in which they are parallel to each other, by using the tow-bar 24 as a lever and locking the slide 29, 29 by the pin or peg 36 to the bar 32. The tow-bar may then be socketed in the rear wheel socket 42 and the crane caused to take any desired path in consequence of manipulation of the operator. The structure, it will be seen, operates as a tricycle with one wheel steering, and can describe circles on a point half way between the two front wheels.

To rotate on a center within the wheel base, the rear wheel is pushed hard over, until it occupies a position at right angles to its fore and aft position and locked in this position by means of the pin or peg 45 so as to operate as a fixed wheel. The tow-bar 24 is then detached and socketed to either of the front wheels. The locking peg 36 is removed and by a sidewise pull the front wheels are swivelled to the required position and pegged or locked in that position by the peg 36. The crane or machine will now be caused to rotate on a center within the wheel base, such rotation being effected either by pulling or pushing on the tow-bar or, if desired, by pulling or pushing the suspended load; or the like.

To traverse the machine, adjustments are effected to bring the front wheels parallel to the rear wheel in its fixed position whereupon the parts are locked as before.

From the foregoing it will be understood that long slewing or short slewing movements may be executed by setting the wheels in appropriate relationships and locking them therein.

Various changes may be made without departing from the invention.

I claim:—

1. In combination, a crane platform, a plurality of wheels on which said platform is

mounted, bearing members for said wheels to permit rotation of said wheels about horizontal axes, means controlled from the ground outside the platform for setting said bearing members about vertical axes at will, said means being rigid with said bearing members and acting directly thereon, and means for positively locking said bearing members in each of the positions in which they may be set.

2. A mobile crane member, three wheels for said member arranged in generally triangular formation to provide a three-point support, two of said wheels being arranged in a pair at opposite side of said member and the third wheel being disposed at one end of said member, lever members rotatable about vertical axes and on which said wheels are mounted for rotation in vertical planes, means for variably setting certain of said lever members controllable from the ground outside of said mobile crane member, and means for positively locking the lever members in set positions.

3. A mobile crane member, three-wheel elements for said member having vertical axes and arranged in generally triangular formation to provide a three-point support, two of said wheel elements being arranged in a pair at opposite sides of said member, the wheels of said elements being rotatable about horizontal axes, and means comprising a detachable lever arm for variably setting said pair of wheel elements about vertical axes, said detachable arm being operative also to move the crane member after the wheels are set.

4. In combination, a crane platform, a plurality of ground wheels on which said platform is mounted, lever members supporting said wheels and rotatable about vertical axes, and means for locking said members in set positions; each of said members having a socket to which a hand-piece may be adapted to variably set said members, and one at least of said lever members having locking devices included in said locking means.

5. In combination, a crane platform, a plurality of ground wheels on which said platform is mounted, lever members supporting said wheels and rotatable about vertical axes, and means for locking said members in set positions; each of said lever members having three arms, one arm providing a bearing for its ground wheel, another arm having a socket for said hand-piece, and the third arm rendering said locking means effective on the lever member.

6. In combination, a crane base, a plurality of ground wheels, supports for said wheels adapted for movement about a vertical axis and in which are rotatably mounted said wheels, a member rigid with each of said supports and to which a detachable hand-piece may be adapted to afford variable settings of said supports about their vertical axes, and

means for locking said supports in set positions, said hand-piece being employed both for the adjustment of said supports and for moving said base and parts thereon.

7. A device of the character described comprising in combination, a mobile base; material-lifting devices thereon; ground-wheel elements for said base; the wheels of said elements being rotatable about horizontal axes, means for variably setting certain of said elements comprising a guide bar on said base, a member slideable longitudinally thereon, and linkages connecting said member to the elements; locking means for the settable elements comprising devices for fixing said slideable member on said guide bar in predetermined positions; and a hand bar operative from the ground outside the device to move the slideable member to predetermined position and also to move the device after the slideable member has been fixed in such predetermined position.

8. A device of the character described comprising in combination, a mobile member, material-lifting devices thereon, three-wheel elements supporting said member, said wheel elements being so disposed as to provide a three-point support, two of said wheel elements being arranged in a pair, the wheels of said elements being rotatable about horizontal axes, means for variably setting said pair about vertical axes comprising a guide bar, a slideable member thereon, and linkages connecting said slideable member to said pair, and a casting in which the third wheel element is housed and which serves as a counterweight.

9. In a crane, the combination of a truck or chassis comprising two side members and an end member rigidly connected together by gusset plates which project beyond the corner of said members, axle members pivotally mounted on projecting portions of said gusset plates, and ground wheels rotatably carried by said axle members, said axle members being provided with arms affording connections for linkage controls and with other arms to receive a push or tow-bar.

10. In a crane, the combination of a horizontal triangular frame composed of two side members and a third member rigidly connected together by gusset plates which project beyond the corners of said members, swivelling axle members mounted on projecting portions of said gusset plates for movement about vertical axes, two ground wheels having horizontal axes carried by said axle members, said axle members being provided with arms affording connections for linkage controls and with other arms adapted to receive a push or tow-bar, said side members of the frame being tied by a casting providing a bearing, a forked bracket supported in the bearing in said casting for pivotal movement about a vertical axis, and a third ground

wheel on said bracket, the forked bracket being provided with a flange adapted to receive said tow-bar.

11. In a crane, the combination of a triangular frame composed of two side members and a third member rigidly connected together, swivelling axle members mounted at the corners of said frame for movement about vertical axes, two ground wheels having horizontal axes carried by two of said axle members, said two axle members being provided with devices affording connections for linkage controls and with other devices for receiving a detachable tow-bar, a connecting element for the side members of the frame, a third ground wheel mounted on said element for pivotal movements about a vertical axis, and a detachable tow-bar on said element for steering the crane from outside said frame.
